(57) **ABSTRACT**

A flexible board, for forming a package, comprises a body portion, a big bottom piece, a small bottom piece, a left-side bottom piece, and a right-side bottom piece. The body portion has a rear body piece, a left-side body piece, a front body piece, and a right-side body piece. The big bottom piece is connected to a lower side of the rear body piece. The small bottom piece is connected to a lower side of the front body piece, and has a strip piece, and first and second projecting pieces. The left-side bottom piece is connected to a lower side of the left-side body piece, and is formed with a cut-out section close to the first projecting piece. The right-side bottom piece is connected to a lower side of the right-side body piece, and is formed with a cut-out section close to the second projecting piece. The length of the insert piece is shorter than the distance between the first and second projecting pieces.

FLEXIBLE BOARD FOR FORMING
PACKAGE

BACKGROUND OF THE INVENTION

1. Field of the Invention

The present invention relates to a package for packaging a commodity such as a camera.

2. Description of the Related Art

Conventionally, there is known a package, in which a commodity having a relatively heavy weight is placed, and the package has a box bottom called an "American Lock", as shown in Japanese Unexamined Patent Publication No. 2000-103422. The box bottom is easily formed by assembling a rear bottom piece, a left-side bottom piece, a front bottom piece, and a right-side bottom piece, so that an operation such as pasting or gluing is not necessary. When viewing the box bottom from the outside, the left-side bottom piece and the right-side bottom piece appear triangular, and the rear bottom piece and the front bottom piece appear trapezoidal, so that the two trapezoids appear to contact at the upper sides, and the oblique sides of the trapezoids appear to contact the oblique sides of the triangles (see FIG. 2 of JUPP No. 2000-103422).

The box bottom of the package described above will not easily open even when the central portion thereof is pressed from the inside, since the rear bottom piece, the left-side bottom piece, the front bottom piece, and the right-side bottom piece are engaged with each other. Thus, a relatively heavy commodity can be contained in the package.

Nevertheless, when information such as the product's serial number has to be indicated on the outer surface of the box bottom, since the conventional box bottom described above is divided into two trapezoids and two triangles, and the dividing lines between the trapezoids and the triangles exist on the central portion of the box bottom, there is a problem in that the area for indicating information is limited. On the other hand, by applying a seal entirely covering the outer surface to the box bottom, the indicating position can be ensured. However, the dividing lines may offset because of jolting during transportation of the packaging, so that the seal is deteriorated, and as a result, the information may become hard to read.

SUMMARY OF THE INVENTION

Therefore, an object of the present invention is to provide a flexible board for forming a package, which ensures that the area for indicating various kinds of information on the outer surface of a box bottom is improved and greater freedom of the indicating position is enabled.

According to the present invention, there is provided a flexible board for forming a package, the flexible board, developed in a plane, comprising a body portion, a big bottom piece, a small bottom piece, a left-side bottom piece, and a right-side bottom piece.

The body portion has a rear body piece, a left-side body piece, a front body piece, and a right-side body piece, which are rectangular, and which are connected to each other to form a strip shape. The big bottom piece is approximately rectangular and is connected to a lower side of the rear body piece. A vertical length of the big bottom piece is approximately equal to a horizontal length of the left-side body piece. The big bottom piece has an insert piece at a tip portion thereof. The small bottom piece is connected to a lower side of the front body piece, and has a strip piece extending along the front body piece, and first and second projecting pieces projecting from both ends of the strip piece in the opposite

2

direction to the front body piece. The left-side bottom piece is connected to a lower side of the left-side body piece, and is formed with a first cut-out section at a portion corresponding to the first projecting piece. The right-side bottom piece is connected to a lower side of the right-side body piece, and is formed with a second cut-out section at a portion corresponding to the second projecting piece. The length of the insert piece in a direction along the rear body piece is shorter than the distance between the first and second projecting pieces.

Further, according to the present invention, there is provided a flexible board for forming a package, which has a polygonal bottom opening when assembled. The flexible board, developed in a plane, comprises a body portion, a big bottom piece, a small bottom piece, a left-side bottom piece, and a right-side bottom piece.

The body portion has a rear body piece, a left-side body piece, a front body piece, and a right-side body piece, which are connected to each other to form a strip shape. The rear body piece is positioned at a side of the polygon opposite to the front body piece in the polygon. The big bottom piece has approximately the same shape of the polygon and is connected to a lower side of the rear body piece. The big bottom piece has an insert piece at a tip portion thereof. The small bottom piece is connected to a lower side of the front body piece, and has a strip piece extending along the front body piece, and first and second projecting pieces projecting from both ends of the strip piece in the opposite direction to the front body piece. The left-side bottom piece is connected to a lower side of the left-side body piece, and is formed with a first cut-out section at a portion close to the first projecting piece. The right-side bottom piece is connected to a lower side of the right-side body piece, and is formed with a second cut-out section at a portion close to the second projecting piece. The length of the insert piece in a direction along the rear body piece is shorter than the distance between the first and second projecting pieces.

BRIEF DESCRIPTION OF THE DRAWINGS

The objects and advantages of the present invention will be better understood from the following description, with reference to the accompanying drawings in which:

FIG. 1 is a perspective view of a package of a first embodiment of the present invention, when viewed from an upper side thereof;

FIG. 2 is a development of the package shown in FIG. 1;

FIG. 3 is a perspective view showing a state midway through an assembling process of the package, in which the package is placed so that the bottom faces upward;

FIG. 4 is a view showing the bottom of the assembled package;

FIG. 5 is a development of the package of a second embodiment of the present invention;

FIG. 6 is a development of the package of a third embodiment of the present invention;

FIG. 7 is an enlarged view showing a third notch formed in the package of FIG. 6;

FIG. 8 is a development of the package of a fourth embodiment of the present invention;

FIG. 9 is a development of the package of a fifth embodiment of the present invention;

FIG. 10 is a development of the package of a sixth embodiment of the present invention; and

FIG. 11 is a development of the package of a seventh embodiment of the present invention.

DESCRIPTION OF THE PREFERRED EMBODIMENTS

The present invention will be described below with reference to an embodiment shown in the drawings.

FIG. 1 is a perspective view of a package of a first embodiment of the present invention, when viewed from an upper side thereof.

The package 10 can be used for containing a camera and an accessory thereof, for example. The package 10 is a rectangular parallelepiped structure, having a body portion 20 with four walls, a pair of side pieces 31, 32, and a lid 33 for opening and closing the upper opening of the body portion 20, and a bottom (not shown). A tip portion 33a of the lid 33 is folded to a side of the body portion 20, and a recess 20a is formed on an upper edge of a front side of the body portion 20 so that the lid 33 is easily opened.

The package 10 is obtained by folding a piece of the flexible board. The flexible board can be paper such as coated paper and cardboard, and may be a thin board made of synthetic resin.

FIG. 2 shows a development view of the package 10.

The body portion 20 has a rear body piece 21, a left-side body piece 22, a front body piece 23, and a right-side body piece 24, which are rectangular, which are connected to form a strip shape. Namely, the rear body piece 21, the left-side body piece 22, the front body piece 23, and the right-side body piece 24 are approximately rectangular, and the boundaries between adjacent pieces are divided by a fold 25. A fastening flap 26 is formed on an edge of the rear body piece 21 opposite to the left-side body piece 22. By folding the folds 25 to form right angles such that the folds 25 face outside, and adhering the fastening flap 26 to an edge of the right-side body piece 24, a quadratic-prism-shape body portion 20 is formed.

A big bottom piece 41 is connected to a lower side of the rear body piece 21. The big bottom piece 41 is approximately rectangular, and a vertical length of the big bottom piece 41 is approximately equal to a horizontal length of the left-side body piece 22. The big bottom piece 41 has a main piece 41a for covering most of a bottom opening of the package 10, and an insert piece 41b formed at a tip portion of the big bottom piece 41.

A small bottom piece 42 is connected to a lower side of the front body piece 23. The small bottom piece 42 has a strip piece 42a extending along the front body piece 23, and first and second projecting pieces 42b and 42c projecting from both ends of the strip piece 42a in the opposite direction to the front body piece 23. Engaging portions 42d and 42e formed between the strip piece 42a and the first and second projecting pieces 42b and 42c appear to be two straight lines that intersect in FIG. 2, but actually are arc-shaped or quadrants.

A left-side bottom piece 43 is connected to a lower side of the left-side body piece 22. The left-side bottom piece 43 is approximately rectangular, and a vertical length of the left-side bottom piece 43 is approximately half the horizontal length of the front body piece 23. The left-side bottom piece 43 is formed with a first cut-out section 43a at a portion close to or corresponding to the first projecting piece 42b. The tip portion of the first cut-out section 43a is a semi-circle or arc-shaped.

Similarly, a right-side bottom piece 44, which is approximately rectangular, is connected to a lower side of the right-side body piece 24. A vertical length of the right-side bottom piece 44 is approximately half a horizontal length of the front body piece 23. The right-side bottom piece 44 is formed with

a second cut-out section 44a, having a semi-circle tip portion, at a portion close to or corresponding to the second projecting piece 42c.

In the big bottom piece 41, the horizontal length of the insert piece 41b in a direction along the rear body piece 21 is shorter than the distance between the first and second projecting pieces 42b and 42c. Further, first and second arc-shaped (or quadrant) notches 41c and 41d are formed between the main piece 41a and the insert piece 41b.

10 The big bottom piece 41, the left-side bottom piece 43, the small bottom piece 42, the right-side bottom piece 44, and the body portion 20 are divided by folds 45. As described above, after the quadratic-prism-shape body portion 20 is formed, the flexible board is folded in such a manner that the folds 45 15 face outside, so that the bottom of the package 10 is formed. This forming process will be described later.

On the other hand, the lid 33 is formed on an upper side of the rear body piece 21. The side piece 31 is formed on an upper side of the left-side body piece 22, and the side piece 32 20 is formed on an upper side of the right-side body piece 24. The lid 33, the side pieces 31, 33, and the body portion 20 are divided by folds 34.

With reference to FIGS. 1 through 4, a forming process of the package 10 is described.

25 A sheet having a shape shown in FIG. 2 is stamped out from a piece of blank board. The sheet is folded at the fold 25 between the left-side body piece 22 and the front body piece 23, and the fastening flap 26 is adhered on a rear surface of the edge of the right-side body piece 24. Thus, a number of the 30 adhered sheets can be stacked up and packaged, and carried to a place where a packing operation for goods is performed.

At the packing area, first, the bottom side of the sheet is turned to the upside, and is expanded so that the body portion 20 becomes a box-shape, while the small bottom piece 42 is 35 folded inside. As shown in FIG. 3, the left-side bottom piece 43 and the right-side bottom piece 44 are then folded inside to overlap on the small bottom piece 42, and further, the big bottom piece 41 is folded in such a manner that the big bottom piece 41 covers the left-side bottom piece 43 and the right- 40 side bottom piece 44.

In this state, when the insert piece 41b of the big bottom piece 41 is depressed, the small bottom piece 42, the left-side bottom piece 43, and the right-side bottom piece 44 are 45 largely deflected downward, so that tip portions 43b and 44b of the left-side bottom piece 43 and the right-side bottom piece 44 are slip under a lower side of the strip piece 42a of the small bottom piece 42. When the depressing force is then 50 released, the small bottom piece 42, the left-side bottom piece 43, and the right-side bottom piece 44, and the big bottom piece 41 are restored, so that a bottom 40 is formed as shown in FIG. 4. Namely, the insert piece 41b is positioned inside the strip piece 42a, and the first and second projecting pieces 42b and 42c are positioned inside the left-side bottom piece 43 and the right-side bottom piece 44. Further, the notch 41c of 55 the big bottom piece 41, the cut-out section 43a of the left-side bottom piece 43, and the engaging portion 42d of the small bottom piece 42 are engaged in an interlocked manner, while the notch 41d of the big bottom piece 41, the cut-out section 44a of the right-side bottom piece 44, and the engaging portion 42e of the small bottom piece 42 are also engaged 60 in an interlocked manner.

As described above, according to the first embodiment, the bottom 40 is assembled only by simply depressing the big bottom piece 41, and therefore, the forming process of the 65 package 10 is simple. Further, due to the engagement of the notch 41c, the cut-out section 43a, and the engaging portion 42d, and due to the engagement of the notch 41d, the cut-out

section 44a, and the engaging portion 42e, the strength of the bottom 40 is ensured, the packed goods are securely held in the package 10. Furthermore, since the tip portions of the left-side bottom piece 43 and the right-side bottom piece 44 are close to each other to cover the whole of the bottom 40, the bottom 40 will not break because of the weight, even if the packed goods are the weight of a medium-size camera for example.

Since the main piece 41a of the big bottom piece 41 has a size which is large enough to cover most of the bottom opening of the package 10, information regarding the goods packed in the package 10 can be freely printed on the bottom 40 without being divided by a division line formed on the bottom in a conventional package. Further, even when a seal, on which such information is printed, is applied on the bottom 40, the area where the seal is applied does not include a division line. Thus, a seal greater than a conventional one can be applied on the bottom 40, and the degree of freedom with which the seal is applied is improved. The seal can be applied not only to the main piece 41a, but also to the rear body piece 21. Accordingly, one seal can be applied over both the rear body piece 21 and the main piece 41a, and thus, a printing process for the seal becomes simpler in comparison with a case in which a plurality of seals are separately applied to the package 10.

Note that, although the notches 41c and 41d, the cut-out sections 43a and 44a, and the engaging portions 42d and 42e are arc-shaped in the embodiment, these can be replaced with curved lines, and are not limited to arc shape. Further, when the sheet material has sufficient strength, such as cardboard or plastic material, the notches 41c and so on need not be formed in a curved line.

The present invention can be applied to a case in which the rear body piece 21 and the front body piece 23 are changed with each other, in the first embodiment. In this case, the big bottom piece 41 is placed between the left-side bottom piece 43 and the right-side bottom piece 44, and the small bottom piece 42 is placed on a left side of the left-side bottom piece 43. Therefore, the first cut-out section 43a is formed on a left side of the left-side bottom piece 43, i.e., a position corresponding to the first projecting piece, and the second cut-out section 44a is formed on a right side of the right-side bottom piece 44, i.e., a position corresponding to the second projecting piece.

FIG. 5 is a development of the package of a second embodiment of the present invention, and the basic structure is the same as that of the first embodiment. The differences from the first embodiment are the shapes of a big bottom piece 51, a small bottom piece 52, a left-side bottom piece 53, and a right-side bottom piece 54.

Namely, in the big bottom piece 51, portions 51d and 51e of a main piece 51a, close to an insert piece 51b, linearly taper off, and notches are not formed on the connecting portion to the insert piece 51b. Further, cut-out sections 53a and 54a formed on the left-side bottom piece 53 and the right-side bottom piece 54 are not semicircular, but are right-angled corners. The small bottom piece 52 has approximately the same shape as that in the first embodiment, and has strip piece 52a, and first and second projecting pieces 52b and 52c. In the small bottom piece 52, however, engaging portions 52d and 52e are not quadrants, but are right-angled corners. On the other hand, vertical lengths of the left-side bottom piece 53 and the right-side bottom piece 54 are slightly greater than those of the first and second projecting pieces 52b and 52c of the small bottom piece 52, and are approximately a quarter of the horizontal length of the front bottom piece 23.

The other structures are the same as those of the first embodiment, and the assembling process is also the same.

According to the second embodiment, in comparison with the first embodiment, discrepancies or offsetting among each 5 of the pieces can be reduced, and the package can be formed with a high accuracy. Further, in the second embodiment, when an edge of the bottom piece catches on something, the problem of the edge rolling up hardly occurs. However, since the strength of the package may not be superior depending 10 upon the size of the package, material such as cardboard and plastic, having sufficient strength, is preferably used for the sheet.

FIG. 6 is a development of the package of a third embodiment of the present invention. The basic structure is basically 15 the same as that of the first embodiment, however, the difference from the first embodiment is a shape of a big bottom piece 61. More specifically, the big bottom piece 61 has a main piece 61a, for covering most of a bottom opening of the package, and an insert piece 61b, and further, a third notch 61c is provided between the main piece 61a and the insert piece 61b. The third notch 61c is formed, as shown in FIG. 7, in such a manner that a notch 61e having an acute angle is 20 provided at a position corresponding to the notch 41c of the first embodiment (see FIG. 2). Namely, the third notch 61c is formed such that an engaging claw 61f, projecting along the longitudinal direction of the insert piece 61b (or in a direction 25 parallel to the rear body piece 21), is formed at the end portion of the insert piece 61b. A contour of the engaging claw 61f contains two straight lines A1 and A2 intersecting at an angle smaller than a right angle. The other structures are the same as 30 those of the first embodiment.

According to the third embodiment, at the bottom of the package, an engaging strength among the notch 61c, a cut-out section 63a of a left-side bottom piece 63, and an engaging portion 62d, and an engaging strength among the notch 61d, a cut-out section 64a of a right-side bottom piece 64, and an engaging portion 62e, are increased, so that heavier goods can be held than with the first embodiment.

FIG. 8 is a development of the package of a fourth embodiment 40 of the present invention. Similarly to the third embodiment, the difference from the first embodiment is a shape of a big bottom piece 71. Namely, in the big bottom piece 71, third notches 71c and 71d are provided between a main piece 71a and an insert piece 71b, to form engaging claws 71e and 71f. The third notches 71c and 71d are deeper in comparison with 45 the third embodiment, and a contour of each of the engaging claws 71e and 71f is curve as a whole. The contour has recesses 71g and 71h, which are formed in positions opposite to the third notches 71c and 71d, and are shallower than the third notches 71c and 71d.

According to the fourth embodiment, similarly to the third embodiment, at the bottom of the package, an engaging strength among the notch 71c, a cut-out section 73a of a left-side bottom piece 73, and an engaging portion 72d, and an engaging strength among the notch 71d, a cut-out section 74a of a right-side bottom piece 74, and an engaging portion 72e, are increased, so that heavier goods can be held than the first embodiment. Further, by providing the shallow recesses 71g and 71h, the insert piece 71b can be snapped under the small bottom piece 72 smoothly, depending upon the material 55 of the package (for example, when the thickness of the material is relatively great).

FIG. 9 is a development of the package of a fifth embodiment 60 of the present invention. Similarly to the third embodiment, the difference from the first embodiment is a shape of a big bottom piece 81. Namely, in the big bottom piece 81, third notches 81c and 81d are provided between a main piece 81a

and an insert piece **81b**, to form engaging claws **81e** and **81f**. The third notches **81c** and **81d** are deeper in comparison with the third embodiment, and a contour of each of the engaging claws **81e** and **81f** is curved as a whole. A shallow recess is not formed, which is different from the fourth embodiment.

According to the fifth embodiment, similarly to the third embodiment, at the bottom of the package, an engaging strength among the notch **81c**, a cut-out section **83a** of a left-side bottom piece **83**, and an engaging portion **82d**, and an engaging strength among the notch **81d**, a cut-out section **84a** of a right-side bottom piece **84**, and an engaging portion **82e**, are increased, so that heavier goods can be held than in the first embodiment.

FIG. 10 is a development of the package of a sixth embodiment of the present invention. The basic structure is the same as that of the third embodiment, and the difference from the third embodiment is a shape of a small bottom piece **92**. Namely, in the small bottom piece **92**, first and second projecting pieces **92b** and **92c** project from both ends of a strip piece **92a** in the opposite direction to the front body piece **23**. Engaging portions **92d** and **92e** formed between the strip piece **92a** and the first and second projecting pieces **92b** and **92c** are rectangular notches. The other structures are the same as those of the third embodiment.

According to the sixth embodiment, similarly to the third embodiment, at the bottom of the package, an engaging strength among the notch **61c**, the cut-out section **63a** of the left-side bottom piece **63**, and the engaging portion **92d**, and an engaging strength among the notch **61d**, the cut-out section **64a** of the right-side bottom piece **64**, and the engaging portion **92e**, are increased, so that heavier goods can be held than in the first embodiment.

FIG. 11 is a development of the package of a seventh embodiment of the present invention.

The package has a hexagonal bottom opening when assembled. Namely, a body portion **100** has a rear body piece **101**, first and second left-side body pieces **102**, **103**, a front body piece **104**, and first and second right-side body pieces **105**, **106**. The rear body piece **101** is located at a side facing the front body piece **104** with respect to the hexagon. The horizontal lengths of these pieces **101** through **106** are identical.

A big bottom piece **111** has a main piece **111a** having approximately the same shape as the opening, and an insert piece **111b** is formed at a tip portion of the big bottom piece **111**. A small bottom piece **112** has the same shape as that of the first embodiment, having a strip piece **112a**, and first and second projecting pieces **112b**, **112c**. A left-side bottom piece **113** is connected to a lower side of the second left-side body piece **103**, which is adjacent to the left-side of the front body piece **104**. A first cut-out section **113a** is formed in a portion adjacent to the first projecting piece **112b**. A right-side bottom piece **114** is connected to a lower side of the first right-side body piece **105**, which is adjacent to the right-side of the front body piece **104**. A second cut-out section **114a** is formed in a portion adjacent to the second projecting piece **112c**. A length of the insert piece **111b**, in a direction along the rear body piece **101**, is shorter than the distance between the first and second projecting pieces **112b** and **112c**.

A hexagon lid **121**, which has the same shape as the opening, is connected to the upper side of the rear body piece **110**. Auxiliary pieces **122** are connected to the upper and lower sides of the first left-side body piece **102**, an upper side of the second left-side body piece **103**, an upper side of the first right-side body piece **105**, and upper and lower sides of the second right-side body piece **106**. The shapes of the auxiliary

pieces **122** can be freely set, and may be expanded to a larger size when the strength of the bottom is required to be improved.

The other structures are identical with the first and second embodiments. The assembling operation is also identical with that of the first and second embodiments, and the description thereof is omitted.

As understood from the seventh embodiment, the present invention is not limited to a package which has a rectangular opening, and can be applied to a package which has an opening shaped like a regular polygon, which has an even number of sides, such as regular hexagon. However, even in the case of a polygon having an odd number of sides, the present invention can be applied to a package, so long as the rear body piece is located at a side which faces the front body piece.

Although the package is assembled by folding one piece of flexible board in the above embodiments, the flexible board can be obtained by connecting or adhering two pieces of flexible board.

Although the embodiments of the present invention have been described herein with reference to the accompanying drawings, obviously many modifications and changes may be made by those skilled in this art without departing from the scope of the invention.

The present disclosure relates to subject matters contained in Japanese Patent Application Nos. 2005-021862 (filed on Jan. 28, 2005) and 2005-290054 (filed on Oct. 3, 2005) which are expressly incorporated herein, by reference, in their entirety.

The invention claimed is:

1. A flexible board for forming a package, said flexible board, developed in a plane, comprising:

a body portion that has a rear body piece, a left-side body piece, a front body piece, and a right-side body piece, which are rectangular, and which are connected to each other to form a strip shape;

a big bottom piece that is approximately rectangular and is connected to a lower side of said rear body piece, a vertical length of said big bottom piece being approximately equal to a horizontal length of said left-side body piece, said big bottom piece having an insert piece at a tip portion thereof;

a small bottom piece that is connected to a lower side of said front body piece, and that has a strip piece extending along said front body piece, and first and second projecting pieces projecting from both ends of said strip piece in the opposite direction to said front body piece;

a left-side bottom piece that is connected to a lower side of said left-side body piece, and that is formed with a first cut-out section at a portion corresponding to said first projecting piece; and

a right-side bottom piece that is connected to a lower side of said right-side body piece, and that is formed with a second cut-out section at a portion corresponding to said second projecting piece;

the length of said insert piece in a direction along said rear body piece being shorter than the distance between said first and second projecting pieces, and a vertical length of each of said left-side and right-side bottom pieces being approximately half a horizontal length of the front body piece.

2. A flexible board according to claim 1, wherein said big bottom piece comprises a main piece, for covering most of a bottom opening of said package, first and second arc-shaped notches being formed between said main piece and said insert piece.

9

3. A flexible board according to claim 1, wherein said big bottom piece comprises a main piece, for covering most of a bottom opening of said package, and a third notch is formed between said main piece and said insert piece such that an engaging claw, projecting in a direction parallel to said rear body piece, is formed at the end portion of said insert piece.

4. A flexible board according to claim 3, wherein said engaging claw comprises a contour, containing two straight lines intersecting at an angle smaller than a right angle.

5. A flexible board according to claim 3, wherein said engaging claw comprises a contour, which is curved as a whole.

6. A flexible board according to claim 3, wherein said engaging claw comprises a contour, which has a recess formed in the opposite position to said third notch.

10

7. A flexible board according to claim 1, wherein an arc-shaped engaging portion is formed between said strip piece and said first and second projecting pieces.

8. A flexible board according to claim 1, wherein said first and second cut-out sections are arc-shaped.

9. A flexible board according to claim 1, wherein, when said flexible board is assembled into said package, said insert piece is positioned inside said strip piece, and said first and second projecting pieces are positioned inside said left-side and right-side bottom pieces.
